CLAIM

The ornamental design for a vehicle scoop hood, as shown and described.

DESCRIPTION

FIG. 1 is a front left perspective view of a vehicle scoop hood showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 top plan view thereof; and,

FIG. 7 is a bottom plan view thereof.

The dash-dot even broken lines illustrate and surround portions of the vehicle scoop hood that form no part of the claimed design.

(Continued)

The “long dash-short dash-short dash” broken lines shown in the drawings illustrate vehicle environmental subject matter which forms no part of the claimed design.
